HATBOX

Aaron Berke, Brooklyn, N. Y.

Application December 13, 1938, Serial No. 245,338

6 Claims. (Cl. 206—8)

The present invention relates to hat boxes having means therein for holding or anchoring the hat against any shift thereof in the box which might cause the trimmings on the hat to be crushed or injured, or the hat to become misshapen.

Heretofore, various forms of such anchoring means have been provided. So far as I am aware, however, such previously existing hat anchors have been constructed independently of the box, as separate articles of manufacture, to be used or omitted at the will of the box manufacturer or dealer.

An object of the present invention is a hat box and anchor formed from one and the same piece of sheet material, by folding such sheet piece, or blank, along fold lines demarcated thereon.

A further object of the invention is a blank of such shape as to involve practically no wastage in the cutting of a multiplicity of such blanks from a single larger sheet, and which, for the shaping thereof into an integral box and anchor, requires no cutouts or loss of material.

A further object of the invention is a system of fold lines and slits in a blank of the character mentioned, such that, without any severing of one part of the blank from the rest of the blank, the combined box and anchor may be formed therefrom by a minimum of manipulations, and with great rapidity.

Other objects and features of the invention will more fully appear upon reference to the accompanying drawings, in which:

Fig. 1 is a top plan view of the combined box and hat holder.

Fig. 2 is a view in cross sectional side elevation, taken on the line 2—2 of Fig. 1.

Fig. 3 is a view in cross sectional side elevation, taken on the line 3—3 of Fig. 1.

Fig. 4 is a plan view of the blank from which the box and anchor are formed.

Referring to the drawings, the box is shown as having a bottom 10, and side walls 11, 12, 13, and 14. The bottom is shown as a single piece, as are also the walls 11 and 13. The wall 12 is made of two pieces 12' and 12''; and the wall 14 in two pieces 14' and 14''. The several sections of the blank shown in Fig. 4 are given the same reference numerals as the box elements which they represent in the erected box.

The opposed single-piece walls 11 and 13 are hinged to the corresponding edges of the bottom 10 on the fold lines 15 and 16. The wall section 11 is laterally extended to have a flap 12' at the left side thereof, and the flap 14' at the right

side thereof. The flaps 12' and 14' are connected to the wall section 11 at fold lines 17 and 18 respectively. These fold lines 17 and 18, in the blank of Fig. 4, are linear extensions of fold lines 19 and 20 which demarcate the left and right edges of the bottom, between the edges 15 and 16 of the latter. In the set up box, the fold line 17 is perpendicular to, and in the same plane with, the bottom edge 19, and the fold line 18 is perpendicular to and in the same vertical plane with the bottom edge 20, in the set up box. The fold lines 21 and 22, which in Fig. 4 demarcate the inner longitudinal edges of the flaps 12' and 14' are, in that figure, shown as linear extensions of the fold line 16 which demarcates the line of connection of wall section 11 to the bottom 10.

Similarly, the wall section 13 is laterally extended to have a flap 12'' at the left side thereof, and a flap 14'' at the right side thereof. Flaps 12'' and 14'' are connected to the wall section 13 at fold lines 23 and 24 respectively; and lines 23 and 24, in the blank of Fig. 4, are linear extensions, respectively, of the fold lines 19—17, and 20—18. In the set up box, fold line 23 is vertical to line 19 and in the same vertical plane with fold lines 19 and 17; and the fold line 24 is vertical to and in the same vertical plane with fold lines 20 and 18. The fold lines 25 and 26, which in Fig. 4, demarcate the inner longitudinal edges of the flaps 12'' and 14'', are in that figure shown as linear extensions of the fold line 16 which demarcates the line of connection of wall section 13 to the bottom 10.

When the box is erected, see Fig. 1, the flaps 12' and 12'', which together form the side walls 12, partly overlap. In the overlapping part of flap 12' is a slit 27; and in the overlapping part of flap 12'' is stamped a hook-shaped tab 28 adapted to be inserted in the slit 27, whereby to lock the two wall sections together. Similarly, when the box is erected, the flaps 14' and 14'', which together form the side wall 14, partly overlap. In the overlapping part of flap 14'' is a slit 29; and in the overlapping part of flap 14' is stamped a hook-shaped tab 30 adapted to be inserted in the slot 29, whereby to lock the two wall sections together.

The sections 12' and 12'' of wall 12 are connected to the edge 19 of the bottom by a web composed of a central part 31 and end parts 32 and 33. A fold line 34, extending across the web from the point of intersection of fold lines 19 and 21, and at an angle of 45 degrees to each of the lines 19 and 21, serves to demarcate the end section 32 of the web from the central section

31 thereof. A fold line 35, extending perpendicularly to the fold line 34, from the point of intersection of fold lines 19 and 25, serves to demark the end section 33 of the web from the central section 31 thereof. A similar web, composed of a central section 36 and end sections 37 and 38, demarked by fold lines 39 and 40, serves to connect the sections 14' and 14'' of wall 14 to the edge 20 of the bottom.

When in the erection of the box, the wall parts 12' and 12'' are swung upward on the fold lines 17, 19 and 23 into a plane perpendicular to the bottom 10, they carry the web sections 31, 32 and 33 with them. If during, or after, this movement, the wall sections 11 and 13 are swung up on the fold lines 15 and 16, into planes perpendicular to the bottom 10, the web will fold on the lines 34 and 35 and be swung into the box, until the web central part 31 lies flat on the upper surface of the bottom, with web end parts 32 and 33 flat on top of the web central part 31—all web parts then lying within the margin 19 of the box bottom. In practice, the wall parts 14' and 14'', with web parts 36, 37 and 38, are swung up simultaneously with the wall parts 12' and 12'' and web parts 31, 32 and 33, so that when the wall sections 11 and 13 are swung as aforesaid, the webs at both sides of the box are simultaneously folded and swung into the box, and down flat against the bottom thereof, in manner aforesaid.

Referring to Fig. 4, it will be noted that that part of the blank lying above the edge 19 of the bottom, and between the wall parts 12' and 12'', is cut through on curves 41 and 42, which incidentally demark the outer edges of the web end sections 32 and 33; and which extends to points 43 and 44 of the web central part 31, partially outlining the latter. The outline of the central web part 31 is completed by a fold line 45, extending from one to the other of the terminal points 43 and 44 of the cuts 41 and 42, parallel to the fold line 19 of the box bottom. Above the fold line 45, and having its inner edge demarked by that fold line and by the cuts 41 and 42, is a flap 46 of general crescent shape, the outer edge 47 of which is formed by a curved cut in the edge of the rectangular blank of Fig. 4. The flap 46 constitutes part of the hat anchor.

Adjacent the bottom 10, between the wall flaps 14' and 14'', is a similar, but conversely shaped flap 48, the inner edge of which is defined by curved cuts 49 and 50 and fold line 51; and the outer edge of which is defined by a curved cut 52 in the edge of the blank. This flap constitutes another part of the hat anchor. These hat anchor parts 46 and 48 are carried into the box body with the web sections 31 and 36 when the wall sections are folded as aforesaid in the erection of the box; and, when so within the box, extend toward, and partly overlap, each other at their ends.

Referring again to Fig. 4, it will be noted that at the upper end of hat anchor part 46, between the lines of cuts 41 and 47, is a hook-shaped end tab 53, and that at the opposite end thereof, between the cuts 42 and 47, is a slit 54. Also at the end of the opposed anchor part 48, between the cuts 50 and 52, is a slit 55, and at the opposite end thereof, between the cuts 49 and 52, is a hook-shaped tab 56.

As shown in Figs. 1, 2 and 3, the hook tab 53 on anchor part 46 is so positioned with respect to the slit 55 in anchor part 48, that hook 53 may be passed into slit 55 to hold the anchor parts to-

gether at one side of the anchor; and the hook tab 56 on anchor part 48 is so positioned with respect to the slit 54 in anchor part 46, that hook 56 may be passed into slit 54 to hold the anchor parts together at the other side of the anchor.

When, therefore, in the erection of the box, the anchor sections 46 and 48 have been swung, with the web sections 31 and 36, into the interior of the box, and the wall sections 12', 12'', 14, and 14'' have been locked in the manner aforesaid, the anchor parts 46 and 48 are swung upward on fold lines 45 and 51 until hook 53 registers with slit 55, and hook 56 with slit 54; whereupon the anchor hooks are inserted into the anchor slits, to form the anchor.

In the modification of the invention shown in the drawings, the anchor parts 46 and 48 are so shaped that the anchor assumes a frusto-conical shape, the upper and lower edges whereof lie in planes parallel to the box bottom. The parts of the blank between the wall flaps may, however, be variously shaped, cut, or provided with fold lines to effect the erection of hat anchors of widely varying styles.

I claim:

1. An article of manufacture, consisting of a sheet having fold lines which define the bottom and side wall elements of a hat box body, two of said fold lines being lines along which two of said side wall elements are hinged to the bottom element, and each of said two side wall elements being laterally extended to include other side wall elements demarked therefrom by other of said fold lines; the sheet being extended outward beyond the bottom element, intermediate said side wall elements, and said intermediate extensions having fold lines and cuts therein which define hat anchor elements hinged to the box-bottom element along an edge of the latter.

2. An article of manufacture, consisting of a sheet having fold lines which define the bottom and side wall elements of a hat box body, each of two of said fold lines, at opposite sides of the box-bottom element, being a line along which one side wall element is hinged to the box-bottom element, and each of said two side wall elements being laterally extended to include other side wall elements demarked therefrom by other of said fold lines; the sheet being extended outward at opposite sides thereof beyond the bottom element, intermediate said opposed wall elements, and said intermediate opposed extensions having fold lines and cuts therein which define hat anchor elements hinged to opposite sides of the box bottom to form the hat anchor.

3. An article of manufacture, consisting of a sheet having fold lines which define the bottom and side wall elements of a hat box body, each of two of said fold lines, at opposite sides of the box-bottom element, being a line along which one side wall element is hinged to the box-bottom element, and each of said two side wall elements being laterally extended to include other side wall elements demarked therefrom by other of said fold lines; the sheet being extended outward at opposite sides thereof beyond the bottom element, intermediate said opposed wall elements, and said intermediate opposed extensions having fold lines and cuts therein which define hat anchor elements hinged to opposite sides of the box bottom to form a conical hat anchor, and which define means for securing said opposed anchor elements one to the other in conical formation.

4. An article of manufacture, consisting of a

sheet having fold lines which define a rectangular bottom and side wall elements of a hat box body, one of the side wall elements being connected to the bottom element along one of said fold lines, and another of said side wall elements being similarly connected to the bottom element at the opposite side of the latter, each of said opposed side wall elements being laterally extended to include other side wall elements defined by other of said fold lines, and said opposed side walls, by means of said extensions, being connectible, one to the other, to form the third and fourth walls of the box body; the sheet being extended outward at opposite sides thereof, beyond the bottom element, intermediate said opposed wall elements, and said intermediate opposed extensions having fold lines and cuts therein which define hat anchor elements hinged to opposite sides of the box bottom, and connectible, one to the other, over the bottom to form the hat anchor.

5. An article of manufacture, consisting of a sheet having fold lines which define a rectangular bottom and side wall elements of a hat box body, one of the side wall elements being connected to the bottom element along one of said fold lines, and another of said side wall elements being similarly connected to the bottom element at the opposite side of the latter, each of said opposed side wall elements being laterally extended to include other side wall elements defined by other of said fold lines, and said opposed side walls, by means of said extensions, being connectible, one to the other, to form the third and fourth

walls of the box body; the sheet being extended outward at opposite sides thereof, beyond the bottom element, intermediate said opposed wall elements, and said intermediate opposed extensions having fold lines and cuts therein which define hat anchor elements hinged to opposite sides of the box bottom, and connectible, one to the other, over the bottom to form the hat anchor, and which define webs for connecting 10 said third and fourth wall elements to the corresponding edges of the bottom element.

15 6. An article of manufacture, consisting of a sheet having fold lines which define the bottom and side wall elements of a hat box body, two of 20 said fold lines being lines along which two of said side wall elements are hinged to the bottom element, and each of said two side wall elements having at least one lateral extension secured thereto along a fold line and functioning in operative position as other side wall elements, sheets 25 integrally connected to said bottom along two other of said fold lines defining said bottom, each of the last named sheets extending outwardly and having fold lines diverging inwardly from its respective fold line; said last named sheets in operative position being inclined with respect to the bottom and overlying the same, and having integrally connected thereto flaps forming anchor parts having means adjacent the ends thereof, 30 each co-operating with means on the other anchor flap to secure said flaps together in operative position.

AARON BERKE.
